CLAIM

The ornamental design for a mid-sized bus, as shown and described.

DESCRIPTION

FIG. 1 is a perspective view, as taken from the front and right side of the mid-sized bus of the present invention.

FIG. 2 is a side view, as taken from the left side of the mid-sized bus of FIG. 1.

FIG. 3 is a side view, as taken from the right side of the mid-sized bus of FIG. 1.

FIG. 4 is a front view of the mid-sized bus of FIG. 1.

FIG. 5 is a back view of the mid-sized bus of FIG. 1.

FIG. 6 is a top view of the mid-sized bus of FIG. 1; and,

FIG. 7 is a bottom view of the mid-sized bus of FIG. 1.

The broken lines shown throughout the drawing are for illustrative purposes only and form no part of the claimed design.
